UNITED STATES PATENT OFFICE.

WILFRED LEWIS, OF HAVERFORD, PENNSYLVANIA.

LEVELING DEVICE FOR MOLDERS' FLASKS.

1,412,882.

Specification of Letters Patent. Patented Apr. 18, 1922.

Application filed March 7, 1921. Serial No. 450,235.

To all whom it may concern:

Be it known that I, WILFRED LEWIS, a citizen of the United States, residing at Haverford, in the county of Montgomery 5 and State of Pennsylvania, have invented a new and useful Leveling Device for Molders' Flasks, of which the following is a specification.

The principal objects of the present invention are first, to cause four wedges to engage with approximately the same force by means of a single operating hand lever; and second, to provide a compact, efficient and reliable leveling device for molders' 15 flasks.

To these and other ends hereinafter set forth the invention, stated in general terms, consists of a leveling device for molders' flasks comprising a hand-lever-turned pinion and two racks, all mounted for motion 20 of translation, and four wedges having equalizing draft gear connecting them in pairs to the racks, whereby the four wedges are made to engage the flask with approximately the same force by means of a single 25 hand lever.

The invention further comprises the improvements to be presently described and finally claimed.

30 In the accompanying drawings forming part hereof is illustrated an embodiment, selected from other embodiments, of the invention, and in those drawings—

Figure 1 is a top or plan view with parts 35 broken away and parts removed.

Fig. 2 is a side view with parts broken away, and

Figs. 3 and 4 are transverse sectional views.

40 In the drawings the bed consists of sides 1 having four wedge pieces 2, and of two cross pieces 3. 4 is a frame movable endwise across the bed and provided with guides 5 co-operating with the cross pieces 3. This 45 frame 4 constitutes a floating or movable center for the pinion 6 which can turn and also partake of a movement of translation because the frame 4 is movable as has been described. 7 is a hand lever for turning the 50 pinion 6, and it is shown as arranged in an opening in the hub 8 of the pinion 6 which is fast to it. 9 and 10 are racks meshing with the pinion 6 and moved endwise in opposite directions by the pinion 6 when it is turned, 55 and these racks as well as the axis of the pinion are all capable of movements of trans-

lation. 11 are four movable wedges, shown as provided with rounded backs 12, and they are slidable on the wedge pieces 2. These wedges are connected in pairs by bars 13 60 which have relative motion in respect to the wedges to which they are connected. The bars 13 are connected with the racks 9 and 10. In the embodiment of invention selected for illustration the connection is not direct, 65 but consists of links 14 pivoted to the bars 13 and to arms 15 of toothed sectors 16 pivoted to the bed 1 and meshing with additional teeth 17 on the racks. 18 are rails afforded rising and falling movement in respect to the bed by pins 19, Fig. 4, and carried by the backs 12 of the wedges 11. 20 are vertically movable brackets or the like for carrying the leveling device.

In use the leveling device is properly positioned for the reception of half molds, use being made of the brackets 20 for that purpose. When a halfmold is brought over the leveling device, for example by the swinging frame of a molding machine from which 70 the half mold is suspended, the hand lever 7 is turned and the power thus applied is exerted upon each of the four wedges 11 through the described mechanism which tends to draw the wedges towards the center 75 of the device raising the rails 18 towards and into contact with the bottom of the half mold. The power thus exerted is applied to the wedges with approximately the same 80 force, because it is equalized regardless of the positions of the wedges since the pinion and racks are all capable of movement of translation and since the bars 13 are movable in respect to the wedges upon which they operate and are themselves along with 85 the links 14 equalizing draft gear. The sectors 16, when present, serve as multiplying devices to augment the wedge movements and permit of the use of wedge angles which will not slip back under load. The rails 18 may be lowered by a reverse movement of the hand lever.

It will be obvious to those skilled in the art to which the invention relates that modifications may be made in details of construction and arrangement without departing from the spirit of the invention which is not limited in respect to such matters or otherwise than as the prior art and the appended claims may require.

I claim:

1. A leveling device for molders' flasks

comprising in combination a pinion and two racks all mounted for motion of translation, four wedges having equalizing draft gear connecting them in pairs to the racks, and a 5 single hand lever for the pinion, whereby the four wedges engage with approximately the same force, substantially as described.

10 2. A leveling device for molders' flasks comprising in combination a pinion and two racks all mounted for motion of translation, and four wedges having equalizing draft gear connecting them in pairs to the racks, whereby the four wedges engage with approximately the same force upon rotary 15 movement of the pinion.

20 3. A leveling device for molders' flasks comprising in combination a single operating hand lever, four wedges, a pinion operated by the hand lever, a center support for the pinion and hand lever capable of movement of translation, two racks movable in opposite directions by the pinion, and equalizing draft gear connecting the wedges in pairs with the racks.

25 4. A leveling device for molders' flasks comprising in combination a single operating hand lever, four wedges, a pinion operated by the hand lever, a center support for the pinion and hand lever capable of movement of translation, two racks movable in opposite directions by the pinion, bars for movably connecting the wedges in pairs, and means for movably connecting the bars and racks.

30 35 5. A leveling device for molders' flasks

comprising in combination a single operating hand lever, four wedges, a pinion operated by the hand lever, a center support for the pinion and hand lever capable of movement of translation, two racks movable in 40 opposite directions by the pinion, bars for movably connecting the wedges in pairs, toothed sectors engaging teeth additionally provided on the racks, and links connecting the sectors and bars.

45 6. A leveling device for molders' flasks comprising in combination a bed, a frame and two racks all movable in respect to the bed, a pinion having an operating handle and journaled on the frame and engaging each rack, four wedges co-operating with wedge pieces provided on the bed, bars movably connecting the wedges in pairs, toothed sectors journaled on the bed and meshing with teeth additionally provided on 50 the racks, links connecting the bars and sectors, and rails co-operating with the wedges, substantially as described.

7. A leveling device for molders' flasks comprising in combination, a bed, a frame 60 and two racks each slidable on the bed, a pinion having an operating handle and journaled on the sliding frame and engaging the racks, four wedges co-operating with wedge pieces provided on the bed, equalizing draft 65 gear connecting the wedges in pairs with the racks, and rails cooperating with the wedges, substantially as described.

WILFRED LEWIS.
